PHOTO-OFFSET PLATE MAKING MACHINE

Albert Gerson, Baldwin Road, Yorktown
Heights, N.Y. 10598

Filed Mar. 10, 1966, Ser. No. 1,401

Term of patent 14 years

(Cl. D61—1)

FIGURE 1 is a front elevational view of a photo-offset plate making machine, showing my new design;

FIGURE 2 is a side elevational view thereof;

FIGURE 3 is a side elevational view thereof, showing the side opposite that seen in FIGURE 2; and

FIGURE 4 is a top plan view thereof.

I claim:

The ornamental design for a photo-offset plate making machine, substantially as shown and described.
